UNITED STATES PATENT OFFICE

114,949

DESIGN FOR A COMBINED COOKING AND SERVING CONTAINER OR SIMILAR ARTICLE

Samuel Hayden and Clair Jacob Amick, Los Angeles, Calif., assignors to Century Metal-craft Corporation, Chicago, Ill., a corporation of Delaware

Application November 28, 1938, Serial No. 81,426

Term of patent 14 years

To all whom it may concern:

Be it known that we, Samuel Hayden and Clair Jacob Amick, citizens of the United States, residing at Los Angeles, in the county of Los Angeles and State of California, have invented a new, original, and ornamental Design for a Combined Cooking and Serving Container or Similar Article, of which the following is a specification, reference being had to the accompanying drawing, forming part thereof.

Fig. 1 is a top plan view of a combined cooking and serving container or similar article showing our new design.

Fig. 2 is a side elevation thereof, partly broken away for convenience of illustration.

The dominant feature of the design resides in the portion shown in solid lines.

We claim:

The ornamental design for a combined cooking and serving container or similar article, substantially as shown.

SAMUEL HAYDEN.
CLAIR JACOB AMICK.
